EARL S. COOK, OF WILMERDING, PENNSYLVANIA, ASSIGNOR TO THE WESTINGHOUSE AIR BRAKE COMPANY, OF WILMERDING, PENNSYLVANIA, A CORPORATION OF PENNSYLVANIA

MULTIPLE SPEED GOVERNOR DEVICE

Application filed January 31, 1929. Serial No. 336,407.

This invention relates to automatic train control apparatus in which the speed of the train is controlled in accordance with traffic conditions.

5 It has heretofore been proposed to provide a train control apparatus of the above type in which a train speed controlled governor or centrifuge is provided for operating a plurality of valves at different train speeds for 10 pneumatically effecting the operation of a brake application valve device in accordance with traffic conditions, the operation of said brake application valve device being adapted to effect an application of the brakes on a 15 train.

The principal object of my invention is to provide a train control apparatus in which the speed of the train may be limited to any one of a plurality of different speed limits, as 20 determined by the traffic conditions, by employing a single speed governor and a single electric switch device.

In the accompanying drawings; Figure 1 is a diagrammatic view, partly in section, of 25 a portion of a train control apparatus showing my invention applied thereto; and Fig. 2 a view, similar to Fig. 1 and showing a modified form of my invention.

As shown in Fig. 1 of the drawings, the 30 train control apparatus comprises a brake application valve device 1, an application magnet valve device 2, two magnet valve devices 3 and 4, signal lights H, M and L adapted to indicate to the operator the track condition, and a speed governor device 5.

The brake application valve device 1 is adapted to control the fluid under pressure in the usual brake pipe 6 and comprises a casting having a chamber 7 containing a piston 8 40 and a valve chamber 9 containing a slide valve 10 adapted to be operated by said piston, outward movement of said piston being opposed by a spring 11 contained in the chamber 7.

45 The application magnet valve device 2 comprises a magnet, valves 12 and 102 adapted to be actuated by said magnet, and a spring 16 acting on valve 102 for seating said valve and unseating valve 12 when the magnet 50 net is deenergized.

For controlling the operation of the magnet of the magnet valve device 2, a toggle switch device, actuated in accordance with the speed of the train, is contained in the speed governor device 5 and is interposed in wires 17 and 18, which are adapted to connect said magnet with a suitable source of electrical energy, preferably a generator 19, which may be driven by any suitable means, such as a rotating part of the locomotive.

The toggle switch hereinbefore mentioned comprises a plurality of pairs of operating arms 20 and 21, and 22 and 23, which are adapted in one position, as shown in the drawings, to engage stationary contacts 24 and 25, and 26 and 27 respectively, for closing the circuit through wires 17 and 18 as hereinbefore described, the contacts 24, 25, 26 and 27, being insulated from each other and rigidly mounted in the casing of the speed governor device 5.

The inner ends of the toggle arms 20 and 21 are operatively mounted on a pin 28, while the inner ends of the toggle arms 22 and 23 are operatively mounted on a pin 29, said pins 28 and 29 being secured to a stem 30 adapted to be moved vertically. The outer ends of said switch arms 20 and 21 are connected by a spring 31, and the outer ends of the arms 22 and 23 are likewise connected by a spring 32, said springs urging the outer ends of said arms toward each other. In the position shown in Fig. 1 of the drawings, with the springs disposed above the axes of the pins 28 and 29, the ends of the arms are urged into engagement with the contacts 24, 25, 26 and 27 respectively. When the stem 30 is shifted upwardly until the pins 28 and 29 pass to the upper side of the springs, the springs then urge the ends of the arms into engagement with stops 33, 34, 35 and 36 respectively, said stops being made of any desirable insulating material and being rigidly mounted in the governor casing.

For moving the stem 30 upwardly in accordance with the train speed, a centrifuge is employed, which comprises weighted arms 37 and 38 fulcrumed on pins 39 and 40, respectively, secured to member 41, which member is adapted to be rotated, when the train

is running, by any desired means, such as by a connection to some rotating part of the train through a plurality of bevel gears 42 and 43 and a shaft 44. The member 41 is 5 provided with a central vertical bore 84 in which an extension of the stem 30 is adapted to slide without rotation thereof upon rotation of said member.

The inner ends of the governor arms 37 10 and 38 are adapted to engage a plate 45 mounted on the stem 30, so that the centrifugal force developed by rotation of said arms will cause said plate to be moved upwardly and thereby shift the stem 30 upwardly 15 wardly.

For the purpose of resisting upward movement of the stem 30, a plurality of springs 46 and 47 are provided to act downwardly thereon, either singly or together, 20 so as to vary the pressure opposing upward movement of the stem 30, the pressure of the springs being set up to oppose movement of the stem in accordance with the traffic conditions, as will be hereinafter more fully 25 explained.

Mounted in the governor casing is a hollow member 100 and the spring 46 is contained in chamber 48 of said member. One end of the spring engages a pusher plate 50 secured 30 to the stem 30, while the upper end of the spring engages a spring seat 71. Said spring seat engages a piston 51 and is provided with a central opening through which the stem 30 extends, said opening forming a guide for 35 the stem. Downward movement of the piston 51 into engagement with a shoulder 52, operates to compress the spring 46, so as to increase the pressure of said spring on plate 50.

40 Surrounding the member 100 and contained in a chamber 53 is the spring 47, which also engages the pusher plate 50, said pusher plate extending through opening 54 provided in said member.

45 Resting on the upper end of spring 47 is a piston 55, which, when in the position shown in the drawings, leaves the spring free of pressure, but which is adapted to be moved downwardly a predetermined distance into engagement with a shoulder 56, in which position said spring is compressed and exerts a predetermined downward pressure on the pusher plate 50. A clearance space is provided above the piston 55, to permit a free upward movement of the spring from the position shown 50 in the drawings.

The H, M and L signal lights may be located in the operator's cab of the locomotive and are so connected through wires 57 and 60, 60 58, 59 and 60, and 61 and 62 with mechanism operative in accordance with the track condition, such as disclosed in the pending application of Thomas H. Thomas, Serial No. 290,917, filed July 7, 1928, for train control 65 apparatus, that said lights will visibly indicate to the operator the track condition, i. e., in clear territory the H signal light will be lighted, in restricted territory the M signal light will be lighted and in dangerous territory the L signal light will be lighted.

70 Connected across the M signal light wires 59 and 60 is the magnet of the magnet valve device 4, which device in addition to the magnet comprises valves 63 and 64 operable by said magnet, and a spring 65 acting on the valve 64 to urge the valves upwardly when the magnet is deenergized.

Connected across the H signal light wires 57 and 58 is the magnet of the magnet valve device 3, which device comprises valves 66 and 67 operable by said magnet, and a spring 68 acting on the valve 67 to urge the valves upwardly when the magnet is deenergized.

Connected across the L signal light wires 80 57 and 58 is the magnet of the magnet valve device 3, which device comprises valves 66 and 67 operable by said magnet, and a spring 68 acting on the valve 67 to urge the valves upwardly when the magnet is deenergized.

In operation, when the track condition is favorable for running at a speed up to the 85 high speed limit, current is supplied to the H signal light so that the signal H lights up. Current is also supplied to the magnet of the magnet valve device 3. Said magnet is thereby energized, seating valve 66 and unseating valve 67, which permits fluid under pressure to flow from any suitable source through a pipe 69, past the unseated valve 67 and through pipe and passage 80 to a chamber 72 at the upper face of piston 55 in the governor. Said piston is thereby moved downwardly into engagement with shoulder 56 in the casing, in which position the spring 47 is compressed a predetermined amount and the pressure of said spring acts downwardly on the pusher plate 50.

The magnet of the magnet valve device 4 being deenergized in high speed territory, spring 65 seats valve 64 and unseats valve 63, thereby connecting the chamber 81 at the upper face of the piston 51 with the atmosphere through passage and pipe 70, past the unseated valve 63 and through the atmospheric passage 82. Thus, in high speed territory, the pressure of spring 47, with piston 55 engaging shoulder 56, plus the initial pressure of spring 46, with the piston 51 in the position shown in the drawings, acts downwardly on the pusher plate 50 and stem 30 to resist the upwardly acting force of the governor arms 37 and 38.

In high speed territory, when a train is running below the high speed limit, the centrifugal force of the governor arms 37 and 38 is insufficient to reverse the position of the toggle switch arms from the position shown in the drawings, against the downwardly acting pressure of springs 46 and 47. Consequently, the circuit is closed through the magnet of the magnet valve device 2, causing 125 said magnet to be energized and to seat valve 12 and unseat valve 102.

Unseating of valve 102 permits fluid under pressure to flow from any suitable source, such as a main reservoir 104 to the piston 130

chamber 7 of the application valve device 1, by way of pipe and passage 103 past valve 102, through chamber 13 and from thence through passage and pipe 15. Fluid under pressure then flows through the choked port 77 in piston 8 into valve chamber 9. When the fluid pressures thereby become equalized on the opposite sides of piston 8, spring 11 urges piston 8 and slide valve 10 to the release position as shown in the drawings, in which position the brake pipe 6 is connected to the usual brake valve device (not shown) by way of cavity 73 in the slide valve 10 and passage and pipe 101, thereby permitting the brake pipe to become charged with fluid under pressure from said brake valve device, in the usual well known manner.

If, in high speed territory, the operator permits a train to exceed the predetermined high speed limit, the centrifugal force developed by rotation of the governor arms 37 and 38 causes an upward thrust on the stem 30 exceeding the downward pressure of the springs 46 and 47, thereby pushing the stem 30 upwardly until the toggle switch arm pins 28 and 29 pass the longitudinal center line of the springs 31 and 32 respectively. Said springs are thereby permitted to rotate the pairs of switch arms 20 and 21, and 22 and 23 around the pins 28 and 29, respectively, and in a downwardly direction until they engage the stops 33, 34, 35 and 36, respectively.

The operation of the toggle switch as just described, opens the circuit through the magnet of the magnet valve device 2. Said magnet is thereby deenergized, which permits spring 16 to seat valve 102 and unseat valve 12 and thereby vent the fluid under pressure from the application piston chamber 7 to the atmosphere through passage and pipe 15, past valve 12 and through the atmospheric passage 14. The pressure of the fluid in the application slide valve chamber 9 acting on piston 8, then causes said piston to move outwardly and compress spring 11. Such outward movement of piston 8 shifts the slide valve 10 to application position in which cavity 73 disconnects the brake pipe 6 from the brake valve (not shown) as hereinbefore described and connects said brake pipe to the atmosphere through an atmospheric passage 74. Fluid under pressure is thereby vented from the brake pipe, which causes an application of the brakes to be effected in the usual well known manner.

After the brakes on the train are applied in the manner hereinbefore described, the speed of the train is reduced, and when reduced to or below the governing speed limit, the centrifugal force of the governor arms 37 and 38 is decreased sufficiently to permit the pressure of springs 46 and 47 to shift the stem 30 downwardly sufficiently to permit the toggle switch arms 20 and 21, and

22 and 23 to return to the position shown in the drawings and thereby again close the circuit through the magnet of the magnet valve device 2, which then operates to cause the application valve device 1 to return to release position in which the brake pipe 6 is again connected to passage 101 from the brake valve and thereby recharged in the manner hereinbefore described.

If the train is operating in medium speed or caution territory the M signal light is lighted and the H and L signal lights are out. Consequently, the magnet of magnet valve device 4, which is connected in parallel with the M signal light, is energized and operates to seat valve 63 and unseat valve 64, which permits fluid under pressure to flow from pipe 69, past the unseated valve 64 and through passage and pipe 70 to chamber 81 at the upper side of piston 51, thereby forcing said piston downwardly into engagement with shoulder 52 and increasing the downwardly acting pressure of spring 46 against the pusher plate 50, a predetermined amount.

With the H signal light out, the magnet of magnet valve device 3 is deenergized, so that the piston chamber 72 of the governor mechanism is at atmospheric pressure due to the connection through pipe and passage 80, past unseated valve 66 and through the atmospheric passage 73. As a result, the spring 47 is permitted to freely expand, as shown in the drawings, and thereby exert no pressure on the pusher plate 50.

The pressure of spring 46, when the piston 51 engages the shoulder 52 is less than the combined pressures of the springs 46 and 47 when operating in high speed territory as hereinbefore described. Consequently, less force is applied to the pusher plate 50 to resist the upwardly acting thrust on stem 30 of the governor arms 37 and 38. As a result, when operating in medium speed territory, if the train speed exceeds the medium speed limit, the centrifugal force developed by the governor arms 37 and 38 exceeds the pressure of spring 46 and operates the toggle switch to effect an application of the brakes in the same manner as hereinbefore described.

If the train is running in dangerous territory, then the L signal light is lighted and the M and H signal lights are out. Both magnets 3 and 4 are thereby deenergized, which operate to connect both piston chambers 72 and 81 to the atmosphere. The spring 46 then expands to the position shown in the drawings, thereby decreasing the downward pressure thereof on the plate 50, and the spring 47 remains ineffective as in medium speed territory. As a result, the centrifugal force of the governor arms 37 and 38 developed at a lower speed of the train is sufficient to operate the toggle switch to apply the brakes in the manner hereinbefore described.

in case the train speed exceeds the low speed limit.

The values of the springs 46 and 47 may be made whatever desired in order to produce the required resistance to operation of the governor arms 37 and 38, so as to obtain the operation of the toggle switch at the required speed limit.

If desired, the governor may be used with 10 train control apparatus in which two speed limits or one speed limit are employed. In the case of two speed limits, the magnet valve device 3 could be eliminated, so that the two speed limits would be governed only by the 15 spring 46 with the piston 51 acting on said spring and operative by the magnet valve device 4, as hereinbefore described, or the magnet valve device 4 could be eliminated and then have the two speed limits governed in 20 one case by the spring 46 when in the position shown in the drawings and governed in the other case by the combined pressures of spring 46 in the position shown in the drawings plus the pressure of spring 47 when the 25 piston 55 is operated by the magnet valve device 3 to engage the shoulder 56.

In Fig. 2 of the drawings is shown a modified construction in which the apparatus is arranged to control the train for only one or 30 two predetermined speed limits. The governor arms 37 and 38 are adapted to operate a stem 85 in an upwardly direction, the upper portion of said stem being slidably mounted in a bore through a wall 86 of the 35 governor casing. Carried by the stem 85 is a spring pusher plate 87 and mounted between said pusher plate and the lower face of the wall 86 is a spring 88 constantly under compression.

Engaging in a cavity at the upper end of 40 the stem 85 is a conical end of a headed push rod 105. The rod 105 extends through an opening in a spring seat 89 and at its lower end, the rod carries a spring seat 90 held in 45 place by a nut 91. A spring 92 is interposed between the spring seats 89 and 90 and urges the spring seat 89 into engagement with a piston 93 having a certain amount of free upward movement and adapted to be moved 50 downwardly a predetermined distance and into engagement with a shoulder 94 in the governor casing.

In operation, if the track conditions are 55 favorable for the train to be run at a high speed, the H signal light is lighted and the magnet of the magnet valve device 3 is energized. The valve 66 is thereby seated, and the valve 67 unseated, which permits fluid 60 to pass through passage and pipe 95 to chamber 96 at the upper side of piston 93. Said piston is thereby moved downwardly into engagement with shoulder 94, thus compressing the spring 92 a predetermined 65 amount. The pressure of spring 92 is trans-

ferred through the spring seat 90 and push rod 105 to the stem 85 and thus supplements the pressure of the spring 88 to resist the upwardly acting thrust of the governor arms 37 and 38 on said stem. In case the operator permits the train speed to exceed the predetermined high speed limit, the centrifugal force of the governor arms moves the stem 85 upwardly against the combined pressures of the springs 88 and 92 and causes the toggle switch to operate so as to effect an application of the brakes in the same manner as hereinbefore described.

If the track conditions are not favorable for high speed operation, then the L signal light is lighted and the H signal light is out. The magnet of magnet valve device 3 is consequently deenergized and spring 68 seats valve 67 and unseats valve 66, thereby venting the fluid under pressure from piston chamber 96 through passage and pipe 95, past the unseated valve 66 and through the exhaust passage 73. The piston 93 is thus free to move upwardly so that the spring 92 will be ineffective. As a result, only the spring 88 is operative to resist the upward thrust of the governor arms 37 and 38, which will therefore be able to operate the toggle switch at a lower predetermined speed than as if both springs were effective.

In both forms of my invention shown in Figs. 1 and 2, it will be noted that failure of the electrical power, the breaking of a wire or the breaking of a pipe will cause either the low speed limit to be automatically imposed upon the train or the brakes will be automatically applied, in the following manner.

If a train is operating in territory in which the signal H or M is lighted, and the current to said signal fails, then the magnet valve device 3 or 4 will operate in the manner hereinbefore described to cause the brakes to be automatically applied, if the train is running at a speed greater than the low speed limit. If the train is running at or below the low speed limit, the brakes will not be applied but since the setting of the governor device is controlled by the magnet valve devices 3 and 4, their deenergization will cause the adjustment to be changed to the low speed in the manner hereinbefore described, so that the train can not then run at a speed greater than the low speed limit. It is obvious that the breaking of a wire to the magnet of either of the magnet valve devices 3 or 4 will also cause the adjustment of the governor device to change to low speed in the same manner as if the current to the magnet fails.

In case the fluid pressure supply pipe 69 should break, then the operation of the magnet valve devices 3 or 4 will be ineffective to change the governor adjustment, and if any of the pipes 70, 80 or 95 from the various magnet valve devices to the governor device

breaks, then the governor device adjustment will not change when the magnet valve device to which a pipe is broken, is energized upon a change in traffic conditions. Consequently, in case of breakage of pipe 70 or 95 the high speed limit will be annulled, if pipe 80 breaks, the medium speed limit will be annulled and the train can then operate only in accordance with the remaining operative portion of the apparatus.

If the current fails or a wire to the magnet of the magnet valve device 2 fails, then said magnet will become deenergized and operate to effect an application of the brakes in the manner hereinbefore described. Failure of the fluid pressure supply to the application piston chamber 7 will also cause an automatic application of the brakes to be effected.

From the above description of my invention, it will be evident that I have provided an apparatus by which the speed of the train can be automatically controlled, so as to limit the speed of the train to any one of a plurality of different speed limits, as determined by the traffic conditions, by means of a single governor device and a single switch mechanism.

In the drawings, the speed governor device has been shown as operating in a vertical position, however, under certain conditions of installation, it may be desirable to operate said governor device in a horizontal or other position, and I therefore do not desire to limit the application of my invention to that shown in the drawings and hereinbefore described.

While two illustrative embodiments of the invention have been described in detail, it is not my intention to limit its scope to these embodiments or otherwise than by the terms of the appended claims.

Having now described my invention, what I claim as new and desire to secure by Letters Patent, is:—

1. The combination with a speed governor, of a member movable by said governor according to the speed, means for opposing the movement of said member by the operation of said governor, and means operated upon an increase in fluid pressure for increasing the force with which the first mentioned means opposes movement of said member.

2. The combination with a speed governor, of a member movable by said governor according to the speed, pressure exerting means for opposing the movement of said member by the operation of said governor, and means operated upon an increase in fluid pressure for increasing in predetermined steps the pressure of said pressure exerting means.

3. The combination with a speed governor, of a member movable by said governor according to the speed, a plurality of springs for opposing the movement of said member by the operation of said governor, and means for at one time simultaneously varying the pressure of said springs and for at another

time varying the pressure of said springs independently of each other.

4. The combination with a speed governor, of a member movable by said governor according to the speed, a plurality of springs for opposing the movement of said member by the operation of said governor, and fluid pressure means for simultaneously increasing the force of said springs in predetermined amounts.

5. The combination with a speed governor, of a member movable by said governor according to the speed, means operative at one time to oppose movement of said member, other means operative at another time to oppose movement of said member, and both means operative at still another time to oppose movement of said member.

6. The combination with a speed governor, of a member movable by said governor according to the speed, and a spring having two different adjusted control positions for controlling the movement of said member.

7. The combination with a speed governor, of a member operable by said governor in accordance with the speed, and a plurality of springs operable at one time singly and at another time collectively to resist the operation of said member at different speeds of said governor.

8. The combination with a speed governor, of a member operable by said governor in accordance with the speed, and two springs operable to govern the operation of said member through three different speed ranges of said governor.

9. The combination with a speed governor, of a member operable by said governor in accordance with the speed, and a spring operable to govern the operation of said member through two different speed ranges of said governor.

10. The combination with a speed governor, of a member operable by said governor in accordance with the speed, yielding means for at all times opposing movement of said member, an additional yielding means, and means for causing said additional means to oppose movement of said member.

11. The combination with a speed governor, of a member operable by said governor in accordance with the speed, yielding means for opposing movement of said member with a predetermined force at one time and fluid pressure means for causing said yielding means to oppose movement of said member with a greater force at another time.

12. In a train control apparatus, the combination with means for effecting an application of the brakes on a train, of a centrifuge operative in accordance with the speed of the train for controlling said means, and means operative to govern the operation of said centrifuge at different speeds of the train.

13. In a train control apparatus, the combination with means for effecting an application of the brakes on a train, of a centrifuge operative in accordance with the speed of the train for controlling said means, and means operative in accordance with traffic conditions for governing the operation of said centrifuge. 70
14. In a train control apparatus, the combination with means for effecting an application of the brakes on a train, of a centrifuge for controlling the operation of said means, a spring operative to oppose the operation of said centrifuge, and means for varying the pressure of said spring according to the traffic conditions. 75
15. In a train control apparatus, the combination with means for effecting an application of the brakes on a train, of a centrifuge for controlling the operation of said means, a plurality of springs operative to control the operation of said centrifuge, and means for varying the pressure of said springs, according to the traffic conditions. 80
16. In a train control apparatus, the combination with means for effecting an application of the brakes on a train, of a centrifuge for controlling the operation of said means, and a plurality of springs arranged one within the other and at one time cooperative with each other to control the operation of said centrifuge. 85
17. In a train control apparatus, the combination with means for effecting an application of the brakes on a train, of a centrifuge for controlling the operation of said means, and a plurality of springs operative either singly or together to control the operation of said centrifuge. 90
18. In a train control apparatus, the combination with means for effecting an application of the brakes on a train, of a centrifuge for controlling the operation of said means, a spring operative to resist the operation of said centrifuge, and a piston carried by said spring and operative to change the pressure of said spring according to the traffic condition. 95
19. In a train control apparatus, the combination with means for effecting an application of the brakes on a train, of a centrifuge for controlling the operation of said means, a spring operative to resist the operation of said centrifuge, a piston carried by said spring, and a magnet valve device operative upon energization to supply fluid under pressure to one side of said piston to compress said spring, said magnet valve device being controlled in accordance with the traffic condition. 100
20. In a train control apparatus, the combination with means for effecting an application of the brakes on a train, of a centrifuge for controlling the operation of said means, a spring operative to oppose the operation of said centrifuge, and electro-pneumatic means for varying the pressure of said spring in accordance with the traffic condition. 105
21. In a train control apparatus, the combination with means for effecting an application of the brakes on a train, of means operative in accordance with the speed of the train for controlling the operation of the first mentioned means, and means operative in accordance with traffic conditions for controlling the operation of the second mentioned means. 110
22. In a train control apparatus, the combination with means for effecting an application of the brakes on a train, of means operative in accordance with the speed of the train for controlling the operation of the first mentioned means, and resilient means operative in accordance with traffic conditions for controlling the operation of the second mentioned means. 115
23. In a train control apparatus, the combination with means for effecting an application of the brakes on a train, of a member responsive to the speed of the train for controlling said means, and a plurality of springs operative to oppose the operation of said means to effect an application of the brakes, the pressure of said springs being automatically varied according to traffic conditions. 120
24. In a train control apparatus, the combination with means for effecting an application of the brakes on a train, of a switch for electrically controlling the operation of said means, means responsive to the speed of the train for operating said switch, and means responsive to the traffic conditions for opposing said speed responsive means. 125
25. In a train control apparatus, the combination with means for effecting an application of the brakes on a train, of a magnet for controlling the operation of said means, a source of electrical energy for supplying current to operate said magnet, a member responsive to the train speed, a snap switch carried by said member and operative to control the electrical circuit through said magnet, and means responsive to the traffic condition for opposing the operation of said member. 130
26. In a train control apparatus, the combination with means for effecting an application of the brakes on a train, of a magnet for controlling the operation of said means, a source of electrical energy for supplying current to operate said magnet, a member responsive to the train speed, a snap switch carried by said member for controlling both sides of the circuit through said magnet, and a spring for opposing the operation of said member, said spring being governed according to traffic conditions. 135
27. In a train control apparatus, the combination with means for effecting an application of the brakes on a train, of a magnet for controlling the operation of said means, a source of electrical energy for supplying current to operate said magnet, a member responsive to the train speed, a snap switch carried by said member for controlling both sides of the circuit through said magnet, and a spring for opposing the operation of said member, said spring being governed according to traffic conditions. 140

nation with means for effecting an application of the brakes on a train, of a magnet for controlling the operation of said means, a source of electrical energy for supplying current to operate said magnet, a member responsive to the train speed, a spring governed by traffic conditions for opposing the operation of said member, and a switch carried by said member for controlling the circuit to said magnet, said switch comprising a pair of arms pivoted on said member, a spring connecting the outer ends of said arms, and two contacts interposed in the circuit of said magnet, the outer ends of said switch arms being adapted to engage said contacts in one position of said member for closing the circuit through said magnet.

28. In a train control apparatus, the combination with a member responsive to the train speed, of means operated by said member for effecting an application of the brakes on a train, a spring seat mounted on said member, a piston movable relative to said member, a spring interposed between said spring seat and piston for at one time opposing the operation of said member with a predetermined pressure, means controlled by traffic conditions for causing said piston to compress said spring for opposing the operation of said member with a different pressure at another time, another spring surrounding the first mentioned spring and engaging said spring seat, a piston carried by said second mentioned spring, and means controlled by traffic conditions for at one time rendering the second mentioned spring ineffective to oppose the operation of said member and at another time for causing it to be compressed to act with the first mentioned spring for opposing the operation of said member.

29. In a train control apparatus, the combination with a snap switch for causing an application of the brakes to be effected, of speed responsive means for operating said switch, a spring for opposing the operation of said speed responsive means, and fluid pressure means operative in accordance with traffic conditions for varying the pressure of said spring.

30. In a train control apparatus, the combination with a snap switch for causing an application of the brakes to be effected, of speed responsive means for operating said switch, resilient means operative at all times to resist the operation of said speed responsive means, and other resilient means for at one time assisting the operation of the first mentioned resilient means and at another time being inoperative to assist.

31. In a train control speed governor device, the combination with a snap switch, of a member carrying said switch, a centrifuge for operating said member, and means for opposing said operation, said means comprising a spring seat on said member, a plu-

rality of springs carried by said spring seat and contained in chambers one within the other, a piston also contained in each of said chambers, one of said pistons engaging one of said springs, the other of said pistons engaging the other of said springs, and fluid pressure means operative in accordance with traffic conditions to control the operation of said pistons for varying the pressure opposing the operation of said centrifuge.

32. In a train control apparatus, the combination with a casing having a plurality of chambers, of a toggle switch in said casing, a member for operating said switch, a centrifuge for operating said member according to the speed of the train, a piston in one of said chambers, a spring interposed between said piston and said member for controlling the operation of said member, the pressure of said spring being adapted to be varied by the operation of said piston, another piston in another of said chambers, a spring interposed between said member and last mentioned piston and adapted to be compressed by the last mentioned piston, for at one time assisting in the control of the operation of said member and at another time being ineffective to control the operation of said member, and means controlled by the track condition for controlling the operation of said pistons.

33. In a train control equipment, the combination with an electrically controlled mechanism for controlling the brakes, of a switch device for controlling the operating circuit of said mechanism, a speed governor for operating said switch, a yielding resistance for opposing the operation of said switch by said governor, and means governed by the traffic conditions for varying the pressure exerted by said yielding resistance.

34. In a train control apparatus, the combination with means for effecting an application of the brakes on a train, a centrifuge for controlling the operation of said means, and a plurality of springs arranged in tandem and operative either singly or together to control the operation of said centrifuge.

In testimony whereof I have hereunto set my hand, this 29th day of January, 1929.

EARLE S. COOK.
